UNITED STATES PATENT OFFICE.

RALPH WALKER, OF ANTLER, NORTH DAKOTA.

EXHAUST-REGULATOR.

1,119,331.

Specification of Letters Patent.

Patented Dec. 1, 1914.

Application filed July 8, 1913. Serial No. 777,977.

To all whom it may concern:

Be it known that I, RALPH WALKER, citizen of the United States, residing at Antler, in the county of Bottineau and State of North Dakota, have invented certain new and useful Improvements in Exhaust-Regulators, of which the following is a specification.

This invention relates to means for regulating the exhaust in that type of traction engines in which the exhaust from the cylinder is utilized to maintain the draft through the fire-box and the boiler.

The object of the invention is to provide simple and easily manipulated means whereby the area of the unobstructed surface at the terminal of the exhaust nozzle may be varied so as to regulate the draft according to the exigencies of any particular set of circumstances.

The invention is illustrated in the accompanying drawings and will be hereinafter fully described, the novel features being subsequently pointed out in the claims following the description.

In the drawings:—Figure 1 is a perspective view of the front end of a traction engine showing my improved attachment applied thereto by dotted lines; Fig. 2 is a transverse section through the lower end of the smoke stack and the front end of the boiler; Fig. 3 is an enlarged plan view of the exhaust nozzle showing my improved attachment in position thereon. Fig. 4 is an enlarged section of the nozzle and the parts adjacent thereto.

The traction engine is constructed with the usual boiler 1 and a smoke stack 2 rising from the free space between the front ends of the fire tubes and the front plate 3 of the boiler. The pipe 4 through which the exhaust steam escapes from the engine cylinder has its front end carried through the wall of the boiler and terminated directly below the smoke stack 2 in an exhaust nozzle 5. The mouth of the nozzle is constructed to present divergent arcs springing upward and outward from the central vertical plane of the nozzle, and damper bars 6 and 7 are adapted to play over the said arcs and seat in the notches formed by the meeting ends thereof. These bars 6 and 7 are of different diameters and are carried by bails or swinging arms 8 which are pivotally attached to the nozzle at the opposite

sides of the same and at the points forming centers of the aforesaid arcs. An operating rod 9 extends through the side of the boiler and is connected at its inner end to a bail or link 10 which is pivotally attached to both of the vibratory arms or bails 8. The said bails with the damper bars carried thereby are consequently caused to swing simultaneously when the operating rod or handle is actuated and the force of the exhaust may be controlled by shifting the damper bars, as will be readily understood.

If the handle or operating rod 9 be moved inwardly to an extent sufficient to hold the bars 6 and 7 at opposite sides of the center of the nozzle and substantially over the edge of the nozzle, the mouth of the nozzle will be unobstructed. If the operating rod be moved outward to its extreme position, as shown in Fig. 2, the smaller rod 6 will seat in the notched mouth of the nozzle and a stronger draft through the fire box will be produced. If the handle be moved inwardly to the limit of its movement, the larger rod or bar 7 will be seated in the notched mouth of the exhaust nozzle and, consequently, a further increase in the draft through the fire-box will be effected. The operating rod or handle is provided with notches 11 in its lower edge adapted to engage the wall of the boiler so as to hold the rod in the position in which it may be set.

It will be readily noted that my device is exceedingly simple in its construction and may be applied to any boiler in which the exhaust from the engine cylinder is utilized to promote the draft through the fire chamber.

What I claim is:—

1. The combination with an exhaust nozzle having seats formed in the edges of its mouth, of damper members of unequal width, and means for simultaneously moving said damper members in the same direction and causing one of them at a time to engage said seats and extend across the center of the nozzle.

2. The combination with an exhaust nozzle, of vibratory members pivotally mounted upon opposite sides of the nozzle, damper rods of different diameters carried by said members, and means for simultaneously operating said vibratory members whereby to hold said rods at the sides of the

nozzle or one of the rods across the mouth of the nozzle.

3. The combination with an exhaust nozzle having its mouth provided with an edge formed on divergent arcs, vibratory members pivotally mounted upon the opposite sides of the nozzle at the centers of the respective arcs, damper devices of different diameters carried by said vibratory mem-

bers, and means for simultaneously operating said vibratory members. 10

In testimony whereof I affix my signature in presence of two witnesses.

RALPH WALKER. [L. S.]
